UNITED STATES PATENT OFFICE.

WALTER L. WHITTEMORE AND PERLEY R. GLASS, OF QUINCY, MASSACHUSETTS, ASSIGNORS TO CHARLES WHITTEMORE, OF NEWTON, MASSACHUSETTS.

EYELETING-MACHINE.

SPECIFICATION forming part of Letters Patent No. 628,289, dated July 4, 1899.

Application filed November 29, 1897. Serial No. 660,070. (No model.)

To all whom it may concern:

Be it known that we, WALTER L. WHITTEMORE and PERLEY R. GLASS, of Quincy, in the county of Norfolk and State of Massachusetts, have invented an Improvement in Eyeletting-Machines, of which the following description, in connection with the accompanying drawings, is a specification, like letters on the drawings representing like parts.

10 The present invention relates to an eyeletting-machine, and is mainly embodied in a novel construction and arrangement of the operative parts whereby the distance between the eyelets set by the machine may be varied

15 and also in an improved gage for the stock, or "spreader," as it may be termed, whereby the distance of the eyelets from the edge of the stock may be varied to obtain the spread or curvature of the line of eyelets as they are

20 now commonly arranged in shoe-uppers.

The invention is herein shown as applied to a machine constructed substantially as shown and described in Patent No. 581,855, granted to Perley R. Glass May 4, 1897, in which the stock is punched and then advanced by an independent feeding device to the eyelet-setting devices, which then operate to set the eyelet in the hole at the end of the punch, and the novel devices which embody the invention will be described in conjunction with such a machine, although it is obvious that such devices might be applied to other machines without departing from the invention.

To vary the distance between adjacent eyelets as they are set in a line by the machine, the punch, in accordance with the present invention, is adapted to be moved laterally with relation to the eyelet-setting devices, and the feed movement is correspondingly adjusted, these two adjustments being effected by common means, so as to maintain the proper relation, the distance between the punch and the eyelet-setting devices obviously being the distance which the stock is required to be moved at each operation of the machine, this distance also being the distance between the adjacent eyelets. In addition to the "permanent adjustment," as it may be called, which may be effected to suit any particular class of work which is to be done,

the machine is further provided, in accordance with the invention, with means whereby the arrangement may be temporarily shifted from its permanently-adjusted position and the feed correspondingly changed at the will of the attendant in the operation of the machine, so that, if desired, there may be a greater distance between some of the eyelets set during one complete run of the machine than there is between others, this variation being accomplished without stopping the machine or changing the permanent adjustment.

The gage or spreader constructed in accordance with the invention comprises an arm or lever which is adapted to engage the edge of the stock and determine the position thereof relative to that of the devices which are to operate thereon, the said gage being controlled by a cam which is adapted during a certain part of a complete run to be moved step by step automatically, thereby changing at each successive operation the position of the stock with relation to the setting devices, so as to produce the spread or curve in the line of eyelets set. The gage and cam both travel with the feeding device, which has a rectilinear movement produced by a swinging lever, and the cam is provided with ratchet-teeth adapted to co-operate with one or the other of a pair of pawls to move the said cam in one direction or the other, the said pawls being mounted on the said lever, and thereby moving on the arc of a circle and operating to advance the cam, which, as stated, is mounted on the slide which moves in a straight line. The said pawls are so arranged, in accordance with the invention, that they can be alternately thrown into engagement with the ratchet-teeth, so as to positively move the cam in either direction at the will of the operator.

Figure 1 is a sectional elevation of a machine embodying the invention; Fig. 2, a partial front elevation thereof; Fig. 3, a vertical section on the line x^3 of Fig. 1; Fig. 4, a sectional detail on the line x^4 of Fig. 3; Fig. 5, a partial top plan view with the parts broken away; Fig. 6, a sectional plan view; Figs. 7 and 8, details, on an enlarged scale, showing the construction of the punch-carrier, Fig. 8

being a longitudinal section on line x^8 of Fig. 7. Fig. 9 is a detail showing an underneath view of a portion of the gage or spreader mechanism, and Fig. 10 a detail showing in section the gage-cam and its bearing.

The machine to which the invention is herein shown as applied is substantially the same in general construction as that shown in the prior patent above referred to, the main operating parts being the punch-lever A, which carries the punch a , the setting devices B B^2 , and the feeding device for the stock, which comprises the slide C and the gripper member C ^{2} , which are connected to and operated by the lever C ^{3} . In the usual operation of the machine the stock is first punched and as the punch rises is carried by the feed-slide C and gripper member C ^{2} a distance equal to the distance between the punch and the setting devices, so that the hole made by the punch is presented to the setting devices, which then operate to insert and set an eyelet. If therefore both the punch and the setting devices are to operate upon the stock and it is desired to set the eyelets at other than the normal distance apart, it is necessary to change the distance between the punch and the setting devices and to correspondingly change the throw or extent of movement of the feed-slide.

As herein shown, the punch a is secured, as by a bolt or screw a^3 , in a carrier a^3 , connected with, but laterally movable with relation to, the lever A. The said carrier is normally pressed laterally into engagement with a pin b , which is longitudinally movable through the projection B ^{3} of the frame which carries the upper eyelet-set B, so that the movement thereof will determine the lateral position of the punch with relation to that of the setting devices. The carrier a^3 is supported and guided in its movement by means of a slotted plate a^4 , suitably secured to the face of a lateral extension A ^{2} of the lever A, the said extension forming, in conjunction with the plate, an actuator or socket for the said carrier a^3 . The said carrier is provided with the slide a^5 at the rear of the plate a^4 , whereby it is retained in the socket. To keep the carrier normally in engagement with the pin b , it is acted upon by the spring a^6 , which is shown as contained in an opening or bore A ^{3} in the lateral extension A ^{2} , the said bore communicating with the guideway or the slide a^5 by means of a slot, into which extends a pin a^7 , connected with said slide to be acted upon by the said spring. For convenience in assembling the said spring is shown as held in position by means of a plate a^8 , fastened to the end of the projection A ^{2} to close the bore and support the end of the spring after it is in position. To adjust the position of the punch with relation to that of the setting devices, therefore, it is necessary only to provide means for longitudinally moving the pin b , this being accomplished by means of an arm b^2 , shown as clamped by means of a cap-

screw b^3 to a rock-shaft b^4 , having a bearing along the side of the extension B ^{3} . The position of the said arm b^2 may obviously be adjusted, if desired, with relation to the rock-shaft by loosening the cap-screw b^3 and again tightening the same after the proper adjustment has been effected. To operate the rock-shaft, it is provided at its opposite end with a lateral projection or arm b^5 , adapted to be operated upon by an extension or lever arm c , mounted upon a hub or boss c^2 , from which extends an operating-arm c^3 , connected, as by a rod c^4 , with an operating treadle or handle. (Not herein shown.) The said arm c is shown as a substantially cylindrical shell open at one side and adapted to engage an enlargement b^6 at the end of the arm b^5 , thereby constituting practically a universal joint, whereby the downward movement of the arm c in response to the movement of the operating device causes a corresponding downward movement of the arm b^5 , whereby the arm b^2 engages the pin b and pushes the same to the left, Fig. 2, thus increasing the distance between the punch and the setting devices. To correspondingly control the extent of movement of the feed-slide C, the hub or boss c^2 is shown as provided with a downward projection c^5 , having a beveled surface c^6 , which is adapted to be engaged by the lever C ^{3} at the end of the movement of said lever in response to its restoring-spring C ^{4} , Fig. 5, to produce the return movement of the feed-slide. That portion of the lever C ^{3} which engages the beveled surface c^6 is correspondingly beveled, it being obvious, therefore, that a movement of the projection c^5 in the direction of the arrow, Fig. 6, will admit of an increased movement of the lever C ^{3} before it is stopped by the said projection, it being obvious, therefore, that when the hub c^2 is rocked by lifting the arm c^3 the result will be not only that the punch is moved farther away from the eyelet-setting devices, but that the lever C ^{3} will have an increased movement before it grips the stock, and consequently will carry the same an increased distance in its forward movement, the limit of which is constant, being determined by the cam C ^{5} , which produced the forward or positive movement of the lever. By the proper relative adjustment, therefore, of the beveled surface c^6 and the arm b^2 , which controls the punch, the distance between the adjacent eyelets may be varied at will. As thus far described, the variation has been shown as accomplished by the upward movement of the arm c^3 , the normal position of the said arm being controlled by the stop projection c^6 , formed on the frame, the said stop projection being engaged by a portion of the hub c^2 or parts movable therewith. In order, therefore, to provide means for primarily adjusting the position of the punch and corresponding throw of the feed, it is necessary only to vary the normal position of the said hub c^2 , and to this end the said hub is shown as provided with a projection c^7 , having an ad-

justing-screw c^8 , the end of which engages the projection c^6 aforesaid. When, therefore, it is desired to permanently change the normal relation of the punch to the eyelet-setting devices, it is necessary only to adjust the said screw c^8 . When, however, a portion of the eyelets are to be set at a certain distance apart and others during the same run of the machine at a greater distance apart, it is desirable to insure uniformity, and to this end the hub c^2 is further provided with a projection c^{20} , corresponding to the projection c^7 , and the adjusting-screw c^{80} , which is adapted to engage the opposite side of the stop c^6 and limit the movement of the hub in response to the movement of the treadle or other actuating device. This movement may also be adjusted, and if it is desired to render the treadle inoperative when it is not desired to use the same and all of the work is to be uniform the hub and the parts controlled thereby may be locked in any desired position by properly adjusting the screws c^8 and c^{80} , so that they both engage with the projection c^6 when the hub c^2 is in the position desired.

The gage for the stock, or "spreader," as it may be called, is herein shown as consisting of a lever-arm d , pivoted at d^2 upon the feed-slide C , the said lever-arm having an engaging portion d^3 , adapted to engage and position the edge of the stock, as best shown in Fig. 6. The said engaging portion d^3 is shown as consisting of a slide-block secured to the arm d by means of a nut d^4 , so that it may be adjusted with relation thereto. The movement of the arm d on its pivot will change the position of the engaging portion d^3 and correspondingly change the position of the stock with relation to the punch and setting devices. To spread the eyelets, therefore, or set the same on a curved line, a step-by-step movement of the gage is produced, whereby the position thereof is changed after each eyeleting operation and prior to the next operation, so that the next eyelet is set in a slightly-different position with relation to the edge of the stock. This is accomplished in accordance with the present invention by means of a cam e , adapted to engage an arm d^5 or extension d^5 of the gage d , the said cam being provided with a series of teeth e^2 and a corresponding series of teeth e^{20} , adapted to be engaged, respectively, by pawls f^2 and f^{20} , which are pivoted at f upon the feed-lever C^3 or an extension therefrom, so that either one of said pawls may be thrown into engagement with its coöperating teeth, the other pawl at the same time being out of engagement with the other teeth. Since the pawls f^2 and f^{20} are mounted, as stated, upon the lever C^3 , their path of travel will be on the arc of a circle and the path of travel of the cam as it is carried by the feed-slide will be rectilinear, so that the relative movements will cause the pawl as it travels in one direction to ride over and catch a tooth and as it travels in the other direction to rotate the cam a certain dis-

tance, the teeth being of such size that the cam will be advanced the distance between two teeth at each feed movement. The teeth are arranged on opposite sides of the cam, so that when one pawl is thrown into engagement with the corresponding teeth it will move the cam in one direction, and if the other pawl is thrown into engagement with its corresponding teeth it will move the cam in the opposite direction. The number of teeth at each side of the cam corresponds to the number of eyelets which are to be spread or set in a different position from the main line of eyelets, and beyond the teeth at each side there is a blank space along which the pawl travels idly back and forth in the feed movement without producing any further movement of the cam.

In the position shown in full lines, Fig. 6, the shoe-upper D is placed in the machine with its edge against the gage, which, as shown, is in its farthest position away from the punch and setting devices which operate upon the stock, so that the first hole eyeleted will be at the maximum distance from the edge. The pawl f^2 is then in engagement with the teeth e^2 and in the feed movement will ride over one of the said teeth, the return movement advancing the cam toward the dotted-line position, so that the gage approaches the punch and setting devices, moving the stock until the edge thereof is nearer the said devices, this operation continuing, so that each eyelet is nearer the edge of the stock than the preceding one, until the dotted-line position is reached, the pawl then having passed beyond the last tooth, so that it produces no further movement of the cam. The operation of the machine then continues, with the gage in its dotted-line position, until the run is finished, and the next upper is then inserted, the mate of the one which has just been finished being the one next operated upon. The first shoe-upper having been placed in the machine so as to travel from its lower end, where the eyelets are spread, toward its upper end, the next shoe-upper will have to be inserted so as to travel from its upper toward its lower end, so that the gage in its dotted-line position will properly position the stock at the beginning of the operation. Toward the end of this operation, however, the eyelets must be again spread, it being essential, therefore, that the gage should move step by step from the dotted-line position back to the full-line position. To this end at the proper period the pawls are shifted by the operator so that the pawl f^{20} coöperates with the teeth e^{20} , thus restoring the cam step by step to the full-line position shown. The gage is shown as provided with a spring d^6 , whereby it is held in engagement with the cam and restored in the reverse movement of said cam. To shift the pawls and retain them in either operative position, the said pawls are shown as provided with an actuating-handle f^3 and a retaining-spring f^4 , the said

retaining-spring being shown as adapted to move the pawls in either direction from a central or neutral position. For this purpose the spring is shown as connected at one end 5 to the part which carries the pawls and at the other end to a part of the machine which is beyond the axis upon which the pawls move, so that a movement in either direction toward a middle or neutral position will strain 10 the spring, which will operate to move the pawl in the opposite direction as soon as the spring crosses the axis. To render the operation of the spring more positive, one end of the same is herein shown as connected to an 15 arm or projection f^6 from the part to which the pawls are connected and at its opposite end to a supplemental arm f^7 , pivoted on the extension f^5 , in which the pawls are supported, the two arms being adapted to intermesh, as 20 by teeth f^{10} on the arm f^6 and a projection f^{10} on the arm f^7 , so that a movement of the end of the arm f^6 in one direction will produce a corresponding movement of the arm f^7 in the opposite direction, the said arms being 25 so arranged that when the pawls are in a neutral position the arms are in alinement with each other and with their pivots, it being obvious, therefore, that the tendency of the spring will be to move them in either direction from the central or neutral position. 30 When the pawl f^2 is in its operative position, as shown, the movement of the feed-lever will tend to carry the same to the left, Fig. 6, and to prevent the spring f^4 from acting to 35 shift the pawls the feed-slide is provided with a stop f^8 to engage the pawl f^2 and retain the same in engagement with the teeth of the cam. By this construction and arrangement 40 the gage is positively moved in each direction, and the operating device for the gage only needs to be shifted once during the operation of the machine for each pair of uppers. The shifting is easily accomplished, requiring only a touch of the finger, so that 45 it is practically impossible to fail to properly operate the machine.

The cam and teeth may be secured to the feed-slide in any suitable or usual way, the said feed-slide being herein shown as provided 50 with a stud e^3 , the cam and teeth being made in one piece, having a bearing on said stud, and being held in position by means of a screw e^4 , Fig. 10. The lower surface of the said cam is preferably provided with a series 55 of radial grooves e^5 , coöoperating with a spring-tongue e^6 , connected with the feed-slide, the said tongue, in conjunction with the grooves, operating as a centering or retaining device to prevent the cam from overthrowing when 60 operated by the pawls.

We claim—

1. In an eyeleting-machine, the combination with the punch of a laterally-stationary actuating-lever therefor, laterally-stationary 65 eyelet-setting devices, a feeding device independent of the punch and setting devices for moving the stock which has been punched to

a position to be operated upon by the setting devices, a stop for limiting the movement of said feeding device, and common means for shifting the position of the punch with relation to its actuating-lever and for moving the limiting-stop for the feeding device whereby the distance between the punch and the setting devices is varied and the length of feed 70 movement correspondingly adjusted, substantially as described. 75

2. In an eyeleting-machine, the combination with the laterally-stationary punch-lever, of the punch movably supported thereon, the eyelet-setting devices laterally stationary with relation to the said punch-lever, a movable projection adapted to determine the position of the punch with relation to its lever, and consequently the distance between said 80 punch and the setting devices, a feeding device for the stock independent of the punch and setting devices, a stop for limiting the movement of said feeding device, and common means for moving the said projection 85 and the said stop to vary the position of the punch and the extent of the feed movement respectively, substantially as described.

3. In an eyeleting-machine, the combination with the punch-lever, of the eyelet-setting devices adjacent to said lever, a punch-carrier movable with relation to the said punch-lever, a spring normally pressing said punch-carrier toward the setting devices, a movable stop projection opposed to said 90 spring and adapted to determine the position of the punch, and means for adjusting the position of said stop projection, substantially as described. 95

4. In an eyeleting-machine, the combination with the punch-lever, of the eyelet-setting devices adjacent to said lever, a punch-carrier movable with relation to said punch-lever, a spring normally pressing said punch-carrier toward the setting devices, a movable 100 stop projection opposed to said spring and adapted to determine the position of the punch, a feeding device for moving the stock from the punch to the setting devices, a limiting-stop for said feeding device, and means for adjusting the position of the punch-stop projection and the limiting-stop for the feeding device, substantially as described. 105

5. In an eyeleting-machine, the combination with the punch-lever, of the eyelet-setting devices adjacent to said lever, a punch-carrier movable with relation to said punch-lever, a spring normally pressing said punch-carrier toward the setting devices, a movable stop projection opposed to said spring and 110 adapted to determine the position of the punch, a rock-shaft having an arm adapted to engage and operate said stop projection, a lever-arm for moving said rock-shaft, a feeding device for the stock, a limiting-stop for 115 the feeding device connected with said lever-arm, and means for adjusting the position of said arm and said stop, substantially as described. 120 125 130 135

6. In an eyeleting-machine, the combination with the punch-lever, of the eyelet-setting devices adjacent to said lever, a punch-carrier movable with relation to said punch-lever, a spring normally pressing said punch-carrier toward the setting devices, a movable stop projection opposed to said spring and adapted to determine the position of the punch, a rock-shaft having an arm adapted to engage said stop projection, a lever-arm for moving said rock-shaft, a feeding device for the stock, a limiting-stop for the feeding device connected with said lever-arm, means for primarily adjusting the position of said lever-arm and said stop, and a device for shifting the same from said primarily-adjusted position, said device being under the control of the attendant, substantially as described.
- 20 7. The combination with the punch-lever, of the setting devices, the punch and punch-carrier laterally movable with relation to the punch-lever, a spring adapted to press the said punch-carrier in one direction, a movable stop projection for determining the position of said punch-carrier, a rock-shaft having an arm adapted to coöperate with said stop projection, a lever-arm for moving said rock-shaft, said lever-arm projecting from a hub 25 or rocker, a feeding device for the stock, a lever for operating the said feeding device, a projection from said rocker extending into the path of said lever and constituting a limiting-stop therefor, means for adjusting the 30 normal position of said rocker, a device for shifting the same temporarily from such normal position, and an adjusting-stop for limiting the distance through which it is thus shifted, substantially as described.
- 35 8. In an eyeleting-machine provided with a punch and setting devices and a reciprocating feeding device for moving the stock from the punch to the setting devices, the combination with the reciprocating member of the 40 feeding device, of a movable gage for the stock connected with said member, a cam co-operating with said gage and adapted by its rotation to move the same, the said cam being rotatably mounted upon the feed-slide, a lever adapted to operate the feed-slide, a pair 45 of pawls carried by said lever, teeth on opposite sides of said cam adapted to be alternately engaged by said pawls respectively, 50

and means for shifting the position of said pawls to throw either one into engagement with the corresponding teeth on the cam, substantially as described.

9. In an eyeleting-machine provided with a punch and setting devices and a reciprocating feeding device for moving the stock from the punch to the setting devices, the combination with the reciprocating member of the feeding device, of a movable gage for the stock connected with said member, a cam co-operating with said gage and adapted by its 60 rotation to move the same, the said cam being rotatably mounted upon the feed-slide, and automatic means for positively rotating said cam in either direction during the operation of the machine, substantially as described.

10. In an eyeleting-machine provided with a punch and setting devices and a reciprocating feeding device for moving the stock from the punch to the setting devices, the combination with the reciprocating member of the feeding device, of a movable gage for the stock connected with said member, a cam co-operating with said gage and adapted by its 75 rotation to move the same, the said cam being rotatably mounted upon the feed-slide, a lever adapted to operate the feed-slide, a pair of pawls carried by the said lever, teeth on opposite sides of said cam adapted to be alternately engaged by said pawls respectively, and a spring arranged to act on said pawls at either side of a central or neutral position, substantially as described.

11. The combination with the gage mounted on the feed-slide, of a cam for operating the same also mounted on the feed-slide, the teeth e^2 and e^{20} , the pawls f^2 and f^{20} adapted to alternately engage said teeth, the arm f^6 connected with said pawls, the arm f^7 coöperating therewith, and the spring f^4 connecting said arms, substantially as and for the purpose described.

In testimony whereof we have signed our names to this specification in the presence of two subscribing witnesses.
